UNITED STATES PATENT OFFICE

BERTRAM L. WATKIN, OF SYRACUSE, NEW YORK, ASSIGNOR TO PASS & SEYMOUR, INC., OF SYRACUSE, NEW YORK, A CORPORATION OF NEW YORK

DESIGN FOR A CEILING LIGHTING FIXTURE

Application filed February 23, 1932. Serial No. 42,959. Term of patent 7 years.

To all whom it may concern:

Be it known that I, BERTRAM L. WATKIN, a citizen of the United States, and resident of Syracuse, county of Onondaga, and State of New York, have invented a new, original, and ornamental Design for a Ceiling Lighting Fixture, of which the following is a specification, reference being had to the accompanying drawings, forming a part thereof, and in which—

Figure 1 is a face view of a fixture incor-

porating the design of the present invention;

Figure 2 is a rear view thereof;

Figure 3 is a fragmentary radial section taken on line 3—3 of Fig. 2; and

Figure 4 is a fragmentary chordal section taken on line 4—4 of Fig. 1.

I claim:

The ornamental design for a ceiling lighting fixture, substantially as shown.

BERTRAM L. WATKIN.
